Primary Examiner — Robin V Webster(74) *Attorney, Agent, or Firm* — Fay Sharpe LLP(57) **CLAIM**

The ornamental design for a paint can insert, as shown and described.

DESCRIPTION

FIG. 1 is a front plan view of the paint can insert showing my new design;

FIG. 2 is a side plan view of the paint can insert of FIG. 1; FIG. 3 is a top plan view of the paint can insert of FIG. 1; FIG. 4 is a front elevation view of the paint can insert of FIG. 1;

FIG. 5 is a bottom elevation view of the paint can insert of FIG. 1;

FIG. 6 is a bottom plan view of the paint can insert of FIG. 1; and,

FIG. 7 is an opposite side view of the paint can insert of FIG. 1.

The broken lines are included for the purpose of illustrating non-claimed subject matter and form no part of the claimed design.

1 Claim, 7 Drawing Sheets(56)
